W. O. DWYER,
STATIONARY INDUCTION APPARATUS,
APPLICATION FILED FEB. 27, 1920.

1,352,360.

Patented Sept. 7, 1920.

Inventor:
William O. Dwyer,

His Attorney.

UNITED STATES PATENT OFFICE.

WILLIAM O. DWYER, OF PITTSFIELD, MASSACHUSETTS, ASSIGNOR TO GENERAL ELECTRIC COMPANY, A CORPORATION OF NEW YORK.

STATIONARY INDUCTION APPARATUS.

1,352,360.

Specification of Letters Patent.

Patented Sept. 7, 1920.

Application filed February 27, 1920. Serial No. 361,702.

To all whom it may concern:

Be it known that I, WILLIAM O. DWYER, a subject of the King of Great Britain, residing at Pittsfield, county of Berkshire, State 5 of Massachusetts, have invented certain new and useful Improvements in Stationary Induction Apparatus, of which the following is a specification.

My invention relates to stationary induction apparatus and has for its general object an improved arrangement of parts whereby there is produced a device of this character, having better electrical properties, at less cost and with more efficient 15 utilization of the materials of construction than has heretofore been accomplished.

It has heretofore been proposed to reduce the insulation employed in windings, particularly those having one end grounded, by 20 bringing the line lead into conducting relation with the windings at the central point of a winding stack, as shown in the application of H. O. Stephens, Serial No. 137,548, in order that such connection will be as far 25 removed from the end iron of the core as possible. By connecting each side of the winding stack in parallel from this central point the charging current also is reduced.

By my invention however a still more desirable electrical effect is accomplished for 30 I employ a condenser element disposed among the windings at the middle point of the winding stack which electrostatically imposes a desired distribution of voltage 35 throughout the coils and coil stack so that it is impossible for high initial and subsequent resonant voltages to build up in the windings or coils by steep wave fronts. I may thus considerably decrease the quantity 40 of insulation previously employed and yet have the desired margin of safety.

It will readily be appreciated that among the advantages had from this construction is an improved space factor due to the need 45 for less insulation, together with a more economical use of the material of construction such as the iron and copper commonly employed.

Other advantages and objects of my invention will appear from the following detailed description when taken in connection with the accompanying drawing in which:

Figure 1 shows a view mainly in vertical section of a transformer having the high 55 voltage winding constructed to embody my

invention. Fig. 2 is a horizontal mid-section of the transformer shown in Fig. 1. Figs. 3 and 4 show details in the constructions employed. And Figs. 5 and 6 are explanatory diagrams.

Referring now to the drawing, and particularly to Fig. 1, I have shown a transformer having a core 10, provided with a cylindrical low voltage winding 11 arranged about the central leg 12 of the core. Externally of this low voltage winding 11 is the high voltage winding 13, which in accordance with my present invention is preferably of the disk-coil construction. The winding 13 is arranged to have a terminal leading 60 to a supply line adapted for connection to the middle point of the winding stack, as shown at 14. Since my invention is particularly applicable to transformers having one terminal of the high voltage winding 65 grounded, the two ends of the coil stack are accordingly indicated as connected to ground as at 15 and 16. The coils of winding 13 are arranged and connected so that the current from the line terminal 14, at any 70 instant, flows in the same direction about the winding axis (which is a single straight line) whether I consider that portion in the group of coils above the center or that in the group below the center. Hence the 75 magnetic flux in the core engendered by the high voltage current has everywhere the same direction at any instant.

At the middle of the high voltage coil stack, I insert the substantially circular conducting plate 20, to effect by condenser action the potential distribution across the upper and lower portions of the coil stack in accordance with my invention. This plate 20 is split, as indicated at 21 in Fig. 2, 85 the ends being insulated apart by means of insulation 22 to prevent a short circuited current from flowing in this element; and is also conductively connected to the line terminal 14 as indicated at 23.

The plate 20 is preferably made from one strip of conducting material, such as steel or copper, and is incased in an insulating jacket 24 as shown in Fig. 3 in a manner substantially similar to that on the coils in 90 the winding 13. By reason of the splitting of the plate 20, as at 21, it may with advantage in some instances be made the first turn of windings in the upper and lower 95 groups of coils of the coil stack since the 100 110

resistance of this plate is substantially zero; but such an arrangement is by no means essential to my invention since it may be preferable to have this plate unrelated to the windings 13 conductively save for the connection 23.

Instead of employing the construction shown in Fig. 3 for the plate 20, I may resort to the construction shown in Fig. 4. 10 Here the conducting plate is made by winding together in disk-coil fashion, uninsulated conductors 30 which are incased in an insulating jacket 34. The conductors 30, form the plate element, but all will be cut 15 through at some point precisely similar to the point 21 in plate 20. A plate element of this type is connected to the line by means of the conductor 23'.

When in operation, a conducting plate of 20 this type in the center of the coil stack, draws a leading or charging current from the line and electrostatically imposes a substantially uniform potential distribution throughout both the upper and lower portions 25 of the coil stack. This will be readily comprehended by reference to Figs. 5 and 6.

In Fig. 5 I have drawn at E lines to represent the electrostatic flux (neglecting edge effects) emanating from the charge on 30 plate 20 for a given instant; the broken lines S being similarly drawn to denote the equipotential surfaces corresponding to the lines E. Since the plate 20 and the yokes of core 10 correspond to the elements of a condenser when the plate 20 is charged, the active portions of which elements are substantially planes, the electrostatic distribution of the potential across the space intervening between these elements will be at 35 substantially a uniform rate. The windings 13' and 13'' inserted in these spaces are, by this condenser action, themselves brought to their desired potential by electrostatic induction without drawing a charging current 40 from the line, or what is the same thing regarded in a different aspect, the shunt capacitance of the windings have been reduced to a substantially negligible value.

In Figs. 6 I have plotted the potential of 50 the coils against turns, when my invention is applied. It is thus seen that for the mean turn of each coil a substantially uniform rate of distribution is accomplished.

Having now described an embodiment of 55 my invention which is at present the best

means known to me for carrying the same into effect, I would have it understood that this is merely illustrative and that I do not mean to be limited thereby to the precise details shown, nor restricted in the choice of 60 recognized equivalents except as defined in my claims hereunto annexed.

What I claim as new and desire to secure by Letters Patent of the United States, is:

1. An electrical winding arranged to be 65 supplied with current at substantially its middle point and to conduct the same in multiple paths diverging from said middle point advancing in the same direction about the winding axis, and provided with means 70 located at said middle point for electrostatically imposing throughout said paths a desired potential distribution.

2. An electrical winding arranged to be 75 supplied with current at substantially its middle point and to conduct the same in multiple paths diverging from said middle point advancing in the same direction about the winding axis, having a condenser element located at said middle point and conductively related to said windings.

3. In an electrical apparatus, the combination with a winding stack having a single rectilinear winding axis, of a terminal connection at substantially the middle of 85 said stack, said winding being arranged to conduct current in parallel paths, one for each section at the side of said connection, both to advance in the same direction about said winding axis, and a condenser element 90 located at the middle of said winding stack arranged to electrostatically induce a substantially uniform potential distribution throughout each winding section.

4. In a transformer and the like, the combination with a core, of a high voltage winding composed of a stack of disk-coils having a single rectilinear winding axis, a conducting element having approximately the dimensions of a disk coil located at substantially the mid point of said stack, said element being conductively connected directly to the line and to the coils at each side thereof, the coils at each side of said element arranged to conduct current in the 100 same direction about said winding axis.

In witness whereof, I have hereunto set my hand this twentieth (20th) day of February, 1920.

WILLIAM O. DWYER.
